CONTROLLING RELAY

John E. Preston, Northport, N. Y., assignor to The American Laundry Machinery Company, Norwood, Ohio, a corporation of Ohio

Original application March 27, 1942, Serial No. 436,465. Divided and this application June 5, 1944, Serial No. 538,847

1. Claim. (Cl. 230—27)

This invention relates to time delay relays of the general form shown, described and claimed in my prior application for Sequence timer and measuring control, Serial No. 436,465, filed March 27, 1942, of which this application is a division.

In said prior application, the time delay relay, shown applied for various uses, such as for measurement or for controlling any operation or apparatus, such as a folding machine, includes an electron discharge valve or device operated by grid control to produce a controlling effect in its output or anode-cathode circuit at critical operating conditions, the period of time delay being varied by causing or producing variation in the rate of change of the operating conditions in the grid circuit during the normal delay period.

The machine being controlled, such as a folding machine, performs its operation upon the work while the work is moving at a substantially uniform rate, but any variation in the rate of work travel results in loss of accurate registry between the operating device and the work at the moment of operation upon the work, causing said operation to be performed at the wrong place.

One object of the invention, therefore, is to provide improved means for compensating for variation in the speed of travel of the work to insure accurate and uniform results.

Another object is to provide a controlling time delay relay of the character described, sensitive to control by variations in the operating conditions of the controlling circuit, and including means operated by or in accordance with the rate of travel of the work, or the speed of operation of the work moving means, for supplying to the control circuit a potential which compensates for speed variation and therefore insures uniform results.

Still another object is to provide a time delay relay of the character described, sensitive to control by variations in grid potential and including means for supplementing the normal controlling variation by a further variation dependent upon or in step with variations in the rate of work travel, all for the purpose described.

Further objects of the invention in part are obvious and in part will appear more in detail hereinafter.

In the drawing, the single view shown, which is a duplicate of Fig. 2 of the drawings of said prior application, is a diagram illustrating the invention applied to a folding machine.

In said folding machine, the control devices are so constructed and arranged that each of a series of articles varying in length, such as napkins,

towels, sheets or the like, and traveling in succession along a definite path, is folded at a definite point or place, proportional to its length; such as at the one-half or mid-point, at the one-third point, or the one-quarter point, or at any other point, always independently of variation in the actual total article length.

In the machine shown, the articles to be folded are advanced from right to left on the upper run of an endless belt or conveyor 10, and as an article thus advances its leading end edge first interrupts the electrical contact between a conducting plate 11 and a first trip device 1, and then between said plate and a second trip device 2, with effects to be later described. As the trailing end edge passes the same trips contact between the plate and said trips is restored, as will be readily understood.

Beyond the second trip 2 the article passes the bite or opening between rotating folding rolls 12, 13, opposite which is a folding blade 14 adapted whenever operated to engage the work and tuck it into the bite of the rolls and thus initiate a transverse fold which is completed by the rolls themselves, the folded article being delivered to trough 16. Blade 14 is actuated by solenoid 15, the operation of which is controlled by the electronic time delay relay system now to be described.

30 Said relay system, in the form shown, includes three standard three-element, separate heater, grid controlled A. C. electron discharge valves A, B, C, two of which, A and B, serve as triggers for controlling the operation of the third, C, which 35 functions as the time delay relay device, as will appear.

Tubes A, B respectively cooperate with trips 1 and 2 to energize or deenergize relay coils 18, 17, tube A and its relay being selected for detailed 40 description because the two sets are generally alike, so that detailed description of both is not necessary.

The filament 19 of tube A is energized from secondary 20 of transformer T, the wiring being 45 partly broken away to simplify the diagram. Grid 21 of tube A is normally biased by resistor 22 to permit the passage of plate current from cathode 23 to plate 24. Under such normal bias, plate current flows through a circuit as follows:

From point 25 in the secondary S of transformer T by way of conductors 26, 27, cathode to plate of tube A, conductor 28, relay 18, and conductors 31, 32, to the secondary S of transformer 50 T. When relay 18 is energized its armature 34

moves from position *b* to position *a*, but this operation takes place only when the grid receives normal bias. Ordinarily such ordinary bias is disturbed and the tube is overbiased, with armature 34 in position *b*, as long as contact trip 1 is in contact with plate 11.

When the trip 1 contacts plate 11 a supplementary bias is imposed on grid 21 by a circuit as follows:

From point 25 of secondary S by way of conductors 26, 27, cathode to grid of tube A, resistor 22, conductor 35, trip contact 1, plate 11, and conductor 36 to voltage divider 37 across the secondary 38 of transformer T. This supplementary grid bias is sufficient to block the flow of plate current in tube A whenever finger 1 is in contact with plate 11.

In similar manner trip finger 2, when in contact with plate 11, imposes a supplementary bias on the grid of tube B, likewise blocking the flow of plate current therethrough and deenergizing relay 17, the armature of which always is in position *b* when finger 2 contacts plate 11.

Tubes A and B therefore serve as triggers in the respective functioning of coils 18, 17, which are therefore sensitive to the passage of articles between plate 11 and trips 1 and 2.

Measurement of the article to determine its actual length, and its positioning at the time of fold, are accomplished or controlled by the third or relay tube or electron discharge device C, as will now appear.

The operation of tube C, as a relay, is controlled by variation of the operating conditions in the controlling grid circuit, such as by variation of the grid potential, and more specifically, in the form shown, by control of the charging and discharging of capacitance or condenser 39, under control of coils 18, 17.

Condenser 39 is charged by means of the rectified half cycle of grid current of tube C. It is being charged only when trip finger 2 touches plate 11 so as to block tube B, deenergize relay 17 and place armature 40 in position *b*. Under those conditions, charging current originating in the voltage divider 37 across secondary 38 flows through a circuit as follows:

From point 25 by conductors 26, 41, cathode to grid of tube C, conductor 44 to capacitance 39, through conductors 45 and 95 to generator 92, then by conductor 96, armature 40 in position *b* and conductor 41 back to voltage divider 37.

The purpose of generator 92 and the manner of discharging of capacitance 39 will be described hereinafter.

As long as capacitance 39 is under charge, its potential is superimposed on the normal bias of tube C, in which the flow of plate current is therefore blocked, so that the armature 48 lies in position *b*. The circuit 55, 54 to coil 15 is open and the folding blade is held retracted.

Whenever condenser 39 has discharged sufficiently to reduce the potential of the grid circuit of tube C to its critical operating value the tube C serves as a relay and passes plate current through a circuit as follows:

From point 25 on secondary S, by way of conductors 26, 41, cathode to plate of tube C, conductor 49, coil 50 and conductor 32 back to secondary S. Coil 50 being thus energized, armature 48 moves to position *a*, and thereupon current flows from the source L₁ by conductor 54 to solenoid 15 and by conductor 55 to L₂. Solenoid 15 thereby is energized, and, in the specific form of machine shown for purposes of illustration, ad-

5
vances and produces a folding operation on the article now in proper position before it.

Discharge of condenser 39 is initiated by engagement of the leading edge of the moving article first with trip 1 and then with trip 2. Engagement with both is necessary.

Engagement with trip 1 opens the biasing circuit through conductor 35 to the grid of valve A, in which plate current flow is therefore established, causing armature 34 to move to position *a*. Likewise, engagement of trip 2 causes the flow of plate current in valve B, causing its armature 40 to move to position *a*. Results are as follows:

Movement of armature 40 away from position *b* opens the charging circuit for condenser 39 before described.

Movement of the two armatures to position *a* establishes a discharging circuit for condenser 39 as follows:

From condenser 39 by wires 45, 95 to generator 92, then by wire 96, armature 40 in *a* position, wire 56, resistor 57, resistor 58, armature 34 in *a* position, and wire 60 back to condenser 39.

The two resistors 57, 58 regulate the rate of discharge, which continues at a uniform rate until the trailing edge of the article passes trip 1, whereupon the biasing circuit for valve A, through conductor 35 is closed. The rise in its grid potential blocks the flow of plate current, coil 18 is deenergized and armature 34 returns to its *b* position.

This operation has the effect of short circuiting resistance 58, by way of wire 58a, out of the discharging circuit for condenser 39. Discharge thereof accordingly proceeds at an accelerated rate, due to the decrease in resistance, until the potential of the grid circuit has been reduced to the critical operating value for the valve. Thereupon the plate circuit of valve C becomes conductive; current flows through coil 50; its armature 48 moves to position *a*; current flows to coil 15; and the folding blade 14 is advanced to perform its customary folding operation.

Finally, when the trailing edge of the article passes trip 2, valve B operates to deenergize coil 17 and reestablish the charging circuit for condenser 39, before described, ready for an operation by and upon the next article.

In the arrangement described, it is apparent that during each cycle of operations condenser 39 is given a definite charge, and its discharge rate is entirely dependent upon the resistance the discharging current encounters in its circuit. In the description above it was assumed that the conveyor belt causes work travel at uniform speed.

It is apparent that a relationship exists between the rate of condenser discharge and the rate of work travel. Thus if the rate of work travel is accelerated after condenser discharge has been initiated the appropriate operation point on the article will have passed beyond the folding blade before the latter is operated, with a consequent error in each such operation.

This can be corrected in several ways, for instance by introducing a compensating variation in the resistance value of the discharging circuit, depending upon article speed, or by varying the value of the condenser charge, dependent on article speed. I have selected the latter expedient, the drawing showing means for opposing a compensating bucking voltage to the charging voltage, with the bucking voltage directing proportional to the rate of advance of the article.

It is apparent that if article speed increases the

condenser discharge should take place in a shorter time, and consequently, in the form shown, the original condenser charge should be smaller. This means that the opposed bucking voltage should be increased if article speed increases, and it is obvious both from abstract consideration and from actual trial that there is a direct relationship between the increase in speed and the required increase in bucking voltage.

For the purpose stated I have introduced into the charging circuit for condenser 39, before described, the current generator 92, said generator being driven in any suitable manner so that its rate of rotation is proportional to the speed of article travel, such as by driving the generator 15 directly from one of the belt driving rollers 93, by belt 94, or in any other suitable manner. This insures a direct relationship between variation in speed of article travel and a change in speed, and consequently in current output, of generator 92.

The generator is so connected in the circuit that its output is opposed in polarity to the charging voltage rectified in valve C. The variable voltage divider 37, across the secondary 38 of transformer T, predetermines the basic charging rate, but the generator 92 supplies whatever compensating bucking voltage is necessary for any given conditions.

In operation generator 92 compensates not only for small speed variations such as might occur during a single cycle of operations of the folding machine, but also for any preselected wider variations chosen for convenience, within reasonable limits. For example, one kind of article may require one speed and another kind of article might be best treated at twice the former speed, etc. Whatever the reasons for variation in the speed or rate of travel of the articles, the generator 92 compensates therefor and insures proper positioning of the operation being performed upon the article in accordance with measurement thereof and proportionately to its length, as described in my said prior application. For example, if the resistances 57, 58 are of such value, both absolutely and relatively to each other, and the capacity 39 is such, that the mechanism functions to fold an article at a point midway of its length, or at a point $\frac{1}{2}$ of its length, regardless of variations in its length, the arrangement described insures that the fold will actually be produced at the pre-

determined point, without variation or error. With the arrangement described, it is clear that the actual charge applied to the capacitance 39, during the charging operation, is dependent upon the compensating effect of generator 92, whose output is opposed to or bucks the output of the normal charging source voltage divider 37. The effect is in step with variations in speed of travel of the belts or tapes carrying the articles to be folded and which serve as the driver for the generator 92. As the speed of travel of the articles increases, the charge of capacitance 39 is reduced by the increased bucking potential supplied by generator 92. The net result is that even though the actual period of maximum time delay may vary from time to time, with variation in speed of article travel, the time delay periods for articles of different length always bear the same proportionate relation to each other, regardless of variations in the speed of article travel. That result is not affected by the fact that generator 92 is also included in the discharging circuit for capacitance 39, because said generator is then ineffective to vary the time of discharge and becomes no more than a current conductor in the discharging circuit, as will be readily understood.

What I claim is:

Apparatus of the character described, comprising means for moving an article along a path, trip means adapted to be engaged by the moving article, time delay relay means variously controlled by said trip means in accordance with variations in length of different articles traveling in said path and including a grid controlled electron discharge device and means for changing the grid potential thereof by sequential steps at different selected rates of change during different steps and for varying the relative duration of the steps of the sequence thereby to cause response by said device delayed over periods varying proportionately as the articles vary in length, and means effective upon said relay means and sensitive to variations in the speed of travel of said article moving means for maintaining uniform the relative duration of the steps of the sequence for any article of given length regardless of variations in the total time delay period consequent upon such speed variations.
